COMBINED CIGARETTE LIGHTER AND WATCH

Hans Lowenthal, London, England

Application August 16, 1954, Serial No. 31,890

Term of patent 14 years

(Cl. D48—27)

Fig. 1.

Fig. 2.

To all whom it may concern:

Be it known that I, Hans Lowenthal, a British subject, residing at Walmar House, 288/292 Regent Street, London, W.1, England, have invented a new, original, and ornamental Design for a Combined Cigarette Lighter and Watch, of which the following is a specification, reference being made to the accompanying drawings, forming a part thereof.

In the drawings:

Figure 1 is a perspective view of the combined cigarette lighter and watch showing my new design; and

Figure 2 is an exploded perspective view thereof.

I claim:

The ornamental design for a combined cigarette lighter and watch, substantially as shown.
